UNITED STATES PATENT OFFICE.

WAYNE H. RICE, OF WINDSOR, CONNECTICUT, ASSIGNOR TO RICHARD W. RICE AND SAMUEL M. RICE, OF SAME PLACE.

DESIGN FOR AN ATOMIZING-TIP FOR SPRAYING APPARATUS.

SPECIFICATION forming part of Design No. 32,399, dated March 27, 1900.

Application filed February 20, 1900. Serial No. 5,970. Term of patent 14 years.

To all whom it may concern:

Be it known that I, WAYNE H. RICE, a citizen of the United States of America, and a resident of East Windsor Hill, in the county of Hartford and State of Connecticut, have invented and produced a new and original Design for an Atomizing-Tip for Spraying Apparatus, of which the following is a specification.

- o This invention relates to atomizing-tips for spraying apparatuses.

In the drawing accompanying and forming part of this specification an atomizing-tip for spraying apparatuses is shown in side elevation, partly in section, embodying my new and original design.

As illustrated in the accompanying drawing, the leading or material feature of my design resides in the peculiar and novel shapes or configurations of the hollow discharging member B and the stream-disseminating or deflecting member D, the former member of which is shaped at its inner end (the lower end as shown in the drawing) to be securely fitted to the discharge end of a nozzle or similar device and has its upper or discharge end shaped to form a cone 2, the apex of which is in alinement with the longitudinal center and discharge-opening 3 in the

main portion of said member B. This conically-shaped portion of the member B has its side faces convexed or curved.

The deflecting member D is shown in the drawing of substantially "gooseneck" configuration, it extending upward in curved lines from the outer or upper end of the member B, at one side thereof, and then forward and downward, terminating at its outer end in a cone-shaped deflector 4, the apex of which is in the form of a plane face 5, disposed at right angles to the longitudinal axis of the member B and which is located in advance of the discharge end of said member B, the center of said cone-shaped deflector 4 being in exact alinement with the longitudinal axis or discharge-opening of the member B.

Having described my invention, what I claim as new, and desire to secure by Letters Patent, is—

The design for an atomizing-tip for spraying apparatus substantially as herein shown and described.

Signed by me at Hartford, Hartford county, Connecticut, this 7th day of October, 1899.

WAYNE H. RICE.
